C. F. MEYER.

NEEDLE BAR FOR FULL FASHIONED MACHINES.

APPLICATION FILED JAN. 23, 1920.

1,420,857.

Patented June 27, 1922.

UNITED STATES PATENT OFFICE.

CHRISTIAN F. MEYER, OF READING, PENNSYLVANIA, ASSIGNOR TO TEXTILE MACHINE WORKS, OF WYOMISSING, PENNSYLVANIA, A CORPORATION OF PENNSYLVANIA.

NEEDLE BAR FOR FULL-FASHIONED MACHINES.

1,420,857.

Specification of Letters Patent. Patented June 27, 1922.

Application filed January 23, 1920. Serial No. 353,503.

To all whom it may concern:

Be it known that I, CHRISTIAN F. MEYER, a citizen of the United States, residing at Reading, in the county of Berks and State 5 of Pennsylvania, have invented certain new and useful Improvements in Needle Bars for Full-Fashioned Machines, of which the following is a specification.

My invention relates to full fashioned 10 knitting machines, and particularly to improved means for maintaining accurate positioning of the movably-carried series of needles with relation to the cooperating sinker and divider mechanism, as fully set 15 forth in connection with the accompanying drawing; the novel features being specifically pointed out in the claims.

Fig. 1 is a partial cross-sectional view of 20 a well-known type of full fashioned knitting machine showing the relation of my improved needle-bar construction to the immediately cooperating parts.

Fig. 2 is a front elevation of a pivotally 25 carried needle-bar embodying my improved construction; the needle-bar shaft and carrying arms thereon being shown.

Fig. 3 is an enlarged rear elevation of the 30 same; Fig. 4 is a corresponding plan view, indicating also the cooperating sinker and divider mechanism; and Fig. 5 is a corresponding end view.

In the machine indicated, the fixed center 35 bed 10 carries the sinker heads 11 arranged in parallel relation to the fixed slur cock 40 guide bar 13, so that uniform operative action upon the usual sinkers and dividers is insured, as required to form uniform loops in the laid thread. These loops however are bent around successive needles 15 of the 45 series carried by needle bar 16, and very accurate positioning of all of these needles with respect to the cooperating loop forming parts already referred to, is essential to the producing of the uniform looping required in high grade product.

The needle bar however is necessarily 50 movable so as to carry its whole body of needles up and down, and also in and out relative to the needle-closing presser plate 17 of the sinker head; the up and down movement being effected as indicated by the lever 20 on needle bar shaft 22; and the in and out movement by rocking the bar upon the pivot end 21 of said lever through a cam-

operated lever 23 connected to a fixed arm 55 24 of the needle bar. Moreover this movably, instead of fixedly, mounted needle bar, is subject to internal structural strains which in the natural "seasoning" of the cast metal commonly employed, frequently causes a 60 warping or change of shape in the considerable length thereof sufficient to quite seriously affect the original careful alinement of the long series of needles. Recognizing the practical seriousness of this difficulty 65 and the essential causes thereof, the primary object of my invention is to provide for easy correction of imperfect alinement as may be required, and I accomplish this by the improved detail construction illustrated. 70

Instead of extending integrally the full length of the machine as do the slur cock bar 13 and center bar 10, the needle bar is ordinarily formed in shorter lengths each adapted to serve as illustrated for two of 75 the series of knitting sections which unitedly form the determined total length; these shorter needle bar parts being all carried and jointly operated by the common needle bar shaft 22 through a series of levers 20 80 on said shaft, as previously described. In my improved construction each of these needle bar lengths comprises a fixed base portion 16 which is carried as usual by the lever 20, and one or more (preferably two as 85 shown) separately formed needle-clamping portions 30; each of the latter forming a knitting section supported upon the upper straight-line surface of the base portion 16, and being independently adjustable upon the 90 latter into or out of parallelism with the fixed slur-cock bar 13.

As shown the pivotal connection of the base portion 16 of the needle bar, to the end 95 of the carrying lever 20, is made adjustable as usual, so as to permit of properly setting said portion bodily relative to the fixed slur-cock bar 13 and the intervening movably mounted sinkers and dividers; so that I have found it practicable to secure in a simple 100 manner the needed nice adjustment of the needle-clamping portion or portions 30 upon the base portion 16, by providing the latter with a midway pivot-pin connection 31 to the base portion, on which pivot, the needle 105 clamping portion is merely turned for adjustment, by means of end set-screws 32, 32 engaging brackets 33, 33 on the base portion,

so as to set the line of needles exactly parallel with the fixed slur-cock bar 13 and presser-plate edge 17 preliminary to rigidly securing the needle-clamping portion to the 5 base portion. The clamping bolts 35, 35 provided for thus rigidly securing the ad-justed needle-clamping portion 30, pass through enlarged openings 36, 36 which per-mit of any required adjusting movements.

10 The separated needle-clamping portions 30 can be manufactured economically, and their convenient independent adjustability upon the base portion of the bar enables the operator to readily maintain the needles in 15 positively correct relation to the fixedly mounted cooperating parts irrespective of any slight but otherwise seriously trouble-some distortion of the needle carrying mech-anism.

20 What I claim is:—

1. In a full fashioned knitting machine having a fixed slur-cock bar and recipro-cating sinkers and dividers; a movable nee-dle-carrying bar comprising a rigid base 25 portion and a separately formed needle-clamping portion pivotally mounted upon said base portion so as to be adjustable thereon into parallelism while retained in fixed longitudinal position thereon.

30 2. In a full fashioned knitting machine having a fixed slur-cock bar and recipro-

cating sinkers and dividers; a movable nee-dle-carrying bar comprising a rigid base portion and a plurality of needle-clamping portions each intermediately pivoted to said 35 base portion and independently adjustable into parallelism while retained in fixed lon-gitudinal position thereon.

3. In a full fashioned knitting machine comprising a fixed slur-cock bar and recip-ro-catively movable sinkers and dividers; a movable needle-carrying bar made up of a rigid base portion, a separately formed nee-dle-clamping portion movably seated upon said rigid base portion in fixed longitudinal 45 position thereon, and means for setting said longitudinal fixed needle-clamping portion into or out of parallelism with said sinkers and dividers.

4. In a full fashioned knitting machine 50 comprising a fixed slur-cock bar and recip-ro-catively movable sinkers and dividers; a movable needle-carrying bar made up of a rigid base portion and a plurality of needle-clamping portions each held in fixed lon-gitudinal position thereon, and means for in-de-pendently setting said longitudinal fixed 55 needle-clamping portions into and out of parallelism with said sinkers and dividers.

In testimony whereof I affix my signature. 60

CHRISTIAN F. MEYER.
